UNITED STATES PATENT OFFICE.

EINAR NEERUP, OF CHICAGO, ILLINOIS.

HYDROMETER-SYRINGE.

1,367,495.

Specification of Letters Patent.

Patented Feb. 1, 1921.

Application filed September 18, 1919. Serial No. 324,411.

To all whom it may concern:

Be it known that I, EINAR NEERUP, a citizen of the United States of America, and a resident of Chicago, in the county of Cook, 5 State of Illinois, have invented certain new and useful Improvements in Hydrometer-Syringes, of which the following is a specification.

This invention relates to a hydrometer 10 for hydrometer syringes or chargometers employed in testing the specific gravity of the acid charges of storage batteries and the like, and has for its object:—

To provide a simple and efficient structural formation and arrangement of parts of improved construction in such devices whereby frictional resistance to the free movement of the hydrometer within the chamber of the syringe is reduced to a minimum and a correct indication afforded during continued use, all as will hereinafter more fully appear.

In the accompanying drawings:—

Figure 1, is a side elevation illustrating 25 the application of the invention to an ordinary form of hydrometer syringe.

Fig. 2, is a detail perspective view of the hydrometer.

Similar reference numerals indicate like 30 parts in both views.

Referring to the drawing, 1 designates the main casing of the syringe formed of glass or like transparent material and preferably of the cylindrical form shown.

35 2 designates the usual operating bulb arranged at the upper end of the casing 1, and 3 designates the usual flexible inlet-outlet tube secured to the lower end of said main casing.

40 A hydrometer is arranged within the casing 1 and adapted to move freely therein with a corresponding influx of the fluid to

be tested into the containing chamber formed by said casing.

5 designates a plurality of strengthening, 45 or reinforcing rings secured in spaced relation to the plain surface or periphery of the bulb 4 of the hydrometer; the said rings being provided, or formed, with a plurality of radial spacing lugs or projections 6 50 which are adapted to bear against the inner wall or surface of the casing 1 to guide the hydrometer in its vertical movement with a minimum amount of frictional resistance to such movement. 55

With the present construction the rings 5 also serve as a guard or protector for the bulb wall or shell of the hydrometer against breakage in handling and shipment, and owing to their separate nature from, and 60 subsequent attachment to said bulb, the weakening and inaccuracies caused by the older formation of bearing points integrally in the shell or wall thereof, is avoided and at the same time greater accuracy and economy in manufacture is attained. 65

Having thus fully described my said invention, what I claim as new and desire to secure by Letters Patent, is:—

A hydrometer comprising a plurality of 70 strengthening rings, secured in spaced relation to the surface of the bulb of the hydrometer, and providing guards for the bulb-wall, each ring having a plurality of radial spacing lugs which are adapted to 75 bear against the inner wall of the syringe with which the hydrometer is employed so as to guide the hydrometer in its vertical movement with a minimum amount of frictional resistance to such movement. 80

Signed at Chicago, Illinois, this 15th day of September, 1919.

EINAR NEERUP.
